MICHAEL WINTER, OF NEW YORK, N. Y.

Letters Patent No. 92,684, dated July 13, 1869.

IMPROVEMENT IN TOBACCO-CUTTING MACHINES.

The Schedule referred to in these Letters Patent and making part of the same.

To all whom it may concern:

Be it known that I, MICHAEL WINTER, of the city, county, and State of New York, have invented a new and useful Improvement in "Tobacco-Cutting Machines," of which the following is a full, clear, and exact description, reference being had to the accompanying drawing, forming part of this specification, and in which—

Figure 1 represents a side view of a tobacco-cutting machine, in part, having my improvement applied to it, with one of the side covers of the machine removed, and

Figure 2, a sectional plan of the same.

Similar letters of reference indicate corresponding parts.

My improvement has reference to machines for making fine-cut tobacco, in which the tobacco is fed and compressed between endless pitched-chain aprons, and delivered through a contracted throat, where it is cut by a revolving knife, arranged to travel across the feed, in close proximity to the throat.

In machines of this description there is constant danger, both as regards breakage of the rapidly-revolving knife, and to the operator in attendance, by flying fragments consequent upon such breakage, by reason of the knife striking the throat-piece, which is produced by the springing or shifting of said throat-piece forward, through pressure of the feeding and compressing-chain or endless travelling platform against it. This is caused by the clogging of the chain and its driving-pinion with gummy matter which oozes from the tobacco during the pressure to which it is subjected in its feed. Such collection of gummy matter also materially interferes with the easy running of the machine.

My invention has for its object the removal of these objections and risks or dangers; and

It consists in the arrangement of a roller, under or at back of the throat-piece, and in proximity to the endless chain at its front end, in a parallel direction to the driving-pinion, so that on any tendency of the endless chain to clog with gum, or of gummy matter to collect between it and its driving-pinion, said roller serves to receive the forward thrust of the chain consequent thereon, thereby relieving the throat-piece of strain, as well as causing the gummy matter to be pressed out from between the chain and pinion, which prevents accumulation of such matter on the chain.

Referring to the accompanying drawing—

A A represent the two cheeks or side covers of the machine, between which are arranged the usual upper and lower endless-chain platforms, arranged to lie at a considerable distance apart in the rear, but approaching each other toward the front or throat-end of the machine, so as to compress into a solid form the tobacco, as they feed it to the throat, where the rapidly-revolving knife works in a crosswise direction to effect the cut.

B is the lower one of these endless chains, which works around a rear roller, C, and on and over a bed, D, and which is driven by a front pinion or toothed driver, E, arranged within it, power being communicated to the shaft of said driver in any suitable manner.

F is the cutting-board or lower throat-piece, lapping down in front, and being extended in the rear, as usual, so as to lie over the forward end of the chain and form a receiving-surface for the tobacco from the endless travelling apron or chain platform B.

Arranged beneath this throat-piece F, and in close proximity to the exterior of the endless chain B, in front, is a cross-roller, G, which serves to receive any forward thrust or displacement of the chain produced by gummy matter from the tobacco getting in between said chain and its driver E, and which furthermore serves, by its keeping the chain in close but free gear with its driver, to squeeze out and prevent the accumulation of such matter on the chain, thus easing the run of the chain and its driver, and relieving the throat-piece F of all strain upon it or tendency to displacement by forward thrust of the chain, whereby all danger of the revolving knife catching or striking the throat-piece is avoided. Said roller G being free to rotate, in no way adds to the friction of the machine.

What is here claimed, and desired to be secured by Letters Patent, is—

The roller G, arranged in relation to the throat-piece F, endless chain B, and its driver E, substantially as and for the purpose or purposes herein set forth.

M. WINTER.
